UNITED STATES PATENT OFFICE.

AMOS M. LONG, OF MONROE, MICHIGAN.

APPARATUS FOR ADMINISTERING ANÆSTHETIC GASES.

SPECIFICATION forming part of Letters Patent No. 294,479, dated March 4, 1884.

Application filed June 6, 1883. (Model.)

To all whom it may concern:

Be it known that I, AMOS M. LONG, of Monroe, county of Monroe, and State of Michigan, have made certain Improvements in Apparatus for Administering Nitrous Oxide and other Anæsthetic Gases, of which the following is a specification.

The object of my invention is to make the common nitrous-oxide-gas apparatus, having a 10 water-cistern containing a gas-chamber resting on the water, with connecting-tubes, chloroform attachment, inhaler, and gas-vessel, more convenient, certain, and quick in operation, and also to economize the narcotizing agents.

15 It consists of the common large upright cistern, B, nearly filled with water, and which is about twelve inches in diameter by thirty inches in height; the movable floating gas-holder A, working vertically within the cistern 20 and nearly filling it in dimension; the cylinder-stand C, for the vessel of compressed gas c; the inhaler 11, with connecting-tubes; a small vapor-making apparatus, 9, of three or four inches in height by one inch in width, 25 and minor details, shown hereinafter.

In the accompanying drawings, Figure 1 is a general view of the exterior of the whole apparatus. Fig. 2 represents the gas-holder in vertical section. Fig. 3 represents the float at 30 the base of the gas-charge in perspective. Fig. 4 represents the same in vertical section. Fig. 5 represents a segment of the periphery of the upper float in vertical section, with its packing. Fig. 6 is a central vertical section of the 35 upper float, showing the packing around the inlet-tube where it enters the gas-chamber. Fig. 7 represents the bottom part of the gas-holder in perspective. Fig. 8 represents one of the floats at the base of the gas-holder. Fig. 40 9 represents the different parts segregated of the vaporizing attachment. Fig. 10 represents the adjusting-weights.

Similar letters of reference indicate like parts in all the views.

45 In Fig. 1, A is the gas-chamber, set down into the wet-cistern B. C is the sheet-metal cylinder or case holding the iron vessel c of compressed gas. 9 is the vaporizing apparatus in position and attached to the inhaler-tube. 11 is the inhaler. a are the depressions in the crown of the gas-holder for the weights.

50 In Fig. 2 the gas-holder and cistern are

shown interiorly by vertical section. At a is shown in cross-section the seats of the weights. They should be of, say, one-fourth inch in 55 depth, and the circumference should correspond with that of the weights, respectively. They are placed in the middle of the crown, so as not to sink the gas-holder obliquely, which would increase the friction along the 60 sides of the cistern. This tall vessel is so sensitive to disturbance of verticity that weights thrown on hastily without guides "list" it over and delay the descent. Heretofore the habit has been to cast on anything at hand, 65 when needed, of anywhere near the suitable weight. A gain of consequence in the use of these graduated weights is that by the increased levity, which may and should be given to the gas-holder, all variations of lung-power, natural 70 or arising from timidity in the subject because of the novel situation, may be provided for with exactitude. Another is that instead of loading with adventitious objects, when at rest, to get the necessary extra pressure on the valves 75 to close them with certainty against leakage, these are always at hand and will not be thoughtlessly removed. Added to this is the facility in loading and unloading the reservoir while 80 operating, as against the delays in the casual way. All these things tend to relieve the operator of the usual distractions at the critical time, so precious to both operator and patient in the control of so arbitrary agents. The space A', between the crown A and the float 85 A², is the gas-chamber, which has heretofore been metallic in the lateral and upper walls only; the floor was water. In mine all the walls are impervious to gas, thus doing away with absorption by the water and escape out 90 below between the walls of the cistern and receiver, and also of deterioration of the gas by the air in the water. A³ is the inlet-tube for the gas. It extends up into the gas-chamber one or two inches above the float A². A⁴ 95 is the water-space below A². A⁵ represents the position of the cone-shaped air-chambers as attached to the face of the gas-holder for floating it.

Figs. 3 and 4 show the great float A², that 100 forms the base of the gas-chamber. Both upper and lower surfaces are convex. It is of thin sheet metal. In the middle portion it is about two or three inches deep, and at the edge

one inch, and has a rubber packing (shown in Fig. 5) at the edge, and another at the annular space around the inlet-tube A^3 , to complete the separation of the gas from the water. It 5 is made about one inch less in horizontal dimension than the cylinder of the gas-holder, to give room at its edge for the obliquely-set packing. The object of this is to make the friction of the packing inappreciable and gain 10 all the advantages of the dry gas-chamber and the wet cistern together, without their disadvantages—a very important advance. No system has before been devised so sensitive in working and so practical, most things considered, as the water-base; but it fails in the economy of gas, which latter I accomplish by the 15 float, Fig. 3, A^2 .

In Fig. 5, A^2 is a segment of the edge of the air-chamber, Fig. 3, with its packing shown 20 at the left. 11 are the seams, in cross-section, that join the metal surfaces, and are made to project, say, one-eighth of an inch horizontally. Over the upper seam, and directed under the lower one, is a band of metal, 2, about one 25 inch in width, for the purpose of projecting the rubber packing obliquely upward and outward toward the vertical walls of the gas-chamber, as shown at 2, and standing farther up than the upper convex surface about one-half inch. 30 On this is laid a thin rubber band, 3, of, say, one-twelfth to one-sixteenth inch thick and about one and one-half inch in width, just wide enough to lay its curtain lightly against the 35 vertical wall of the gas-chamber, and about one-eighth to one-fourth inch upon it. Around this rubber band, toward its lower edge, is tightly drawn a fine thread of wire, 4, (shown in cross-section by the dot,) to confine it rigidly to place, so that the upper edge of the rubber 40 band may not buckle and turn the pressure of the gas behind the upper edge of the rubber curtain, thus diverting the packing from its purpose. Outside of the wire and of the rubber band is another metal band, 5, resting its 45 base against the lower seam, 1, and extending upward about two-thirds of the width of the rubber band, leaving the rest of it free to accommodate itself to any inequalities in the receiver-wall. Upon the convex upper surface 50 of A^2 , close to the edge, is a metal band, 6, projecting nearly horizontal, and resting against the curtain of 3 and above the band 2, to cure any remaining tendency in 3 to buckle or crinkle, to insure its uniform adhesion to the 55 reservoir-wall, and yet not to interfere with its freedom of adaptation to the wall, and also to insure its facile vertical movement.

In Fig. 6 is shown a central vertical section of the float, Fig. 3, containing the passage 60 through it for the inlet-tube with the packing i and the packing-tube h , the latter not in section. It consists of an aperture, g , through the float, which is closed laterally, of course. The *lumen* of this passage should be about 65 two inches. Into it is inserted a tube, h , of two or three inches in length, with the lower end projecting enough below the float to grasp

it for retraction, and extending well up into the aperture g , so nearly filling it that a thin diaphragm of rubber, i , drawn lightly over 70 the upper end of the tube h and tied down between the walls of h and g , will just pack it moderately close. In the middle of this diaphragm is a small opening, of, say, one-fourth inch, through which the inlet-tube A^3 passes, 75 so that the rubber will hug around the tube and complete the gas-proof condition of the chamber A' . The aperture g is made purposely larger than the inlet-tube to promote the mobility of the float, Fig. 3, both lateral 80 and vertical, that it may accommodate itself to any oscillation and to the varying stages of water.

In Fig. 7 are shown the flotation-chambers of the gas-holder A . A^5 shows the position 85 and proportion of the bases of the four air-chambers, Fig. 8, attached to the bottom and within A . A^6 shows the spaces between them for ingress and egress of the water, while Fig. 8 shows entire one of the air-chambers. They 90 should be about nine or ten inches in height, about seven or eight inches at their greatest width, and about five inches radially. This is a gain over the old way with the one broad float that shuts up the whole *lumen* of the 95 holder, except the small annular space around the inlet, delaying the flow of gas to the patient, because of the dilatory movement of the water into the holder to take the place of the consumed gas, especially affecting a perverse 100 subject. They are attached to the wall of the cylinder A by their plane or *plano-convex* side, and so temporarily, by any well-known means, as to be readily removed when necessary to get at the upper interior of it. 105

In Fig. 9, d is a glass vessel of some two ounces capacity for the chloroform. It has a male screw-thread on the outside of the neck, which fits into the female thread on the inner base of the metal case D . Above this neck-joint is a valve across the *lumen* of D , of two half-circles of metal. (Shown at $d'd'$.) One of these is rigid; one is movable and revolves around a pivot in the center by the handle d' , through a slot, d^2 , in the case D . Below the 110 glass vessel d is another metal case, e , containing a lamp, e' , which is extinguished by closing the sliding door e^2 . This vapor apparatus is clasped to the inlet A^3 , by the clip and the thumb-screw e^3 , and is joined to the inlet-tube 115 by the neck d^4 at the top. The vapor is shut off by the valve $d'd'$. This is a gain in time and material over the cold method of vaporizing the chloroform by spilling it into the tubes in excess to insure the needed quantity 120 of fumes in time for the operation.

The weights, Fig. 10, are dishes of metal, with large central openings for the quick grasping of them, and are "raised" or bowl-formed for that purpose, and also to "nest" when out of 130 use, and are of such widths as to fit into the corresponding depressions, a , in the crown of the gas-holder, and should be of two, four, and eight ounces weight, and are selected and ap-

plied according to the levity of the gas-holder, and to accommodate the lung capacity and other circumstances of each case. They are a gain over the old method of throwing on anything at hand.

The common way of operating such machines is, first, a few gallons—say five or six—are let into the gas-holder for a charge, and along with it is carried the vapor from the chloroform spilled into the gas-tubes, either by guess in any crude way, or, not much better, through a turn-cock set in the tubes, depending on ordinary evaporation of the drippings. This is of course slow and uncertain in an operation that needs so much celerity, and certainty also, as this. The gas-holder is hurried down into the cistern by the hand or by any means, and when done the gas-holder is fastened down by a wedge between the holder and the cistern, to the damage of the thin sheet-metal gas-holder by indentations, or the holder is loaded with books or tools. I obviate these crude methods by means of the evaporator and the weights. It is obvious that a lamp of a given heating capacity in a given time will be far more certain of proper result than any of the crude spilling methods, quicker, and that the quantity is entirely under the control of the operator.

I am aware of similar apparatus in general principle being made and used—*i. e.*, with the cistern B, gas-holder A, cylinder-holder c, and a single broad float at the base of the gas-holder, with inlet and outlet tubes with chloroform-

inlet cups—and I do not claim any of these; but What I do claim, and desire to secure by Letters Patent, is—

1. In an apparatus for administering anaesthetic gases, the combination of gas-holder A, floating partition A², having a central opening for supply or inlet pipe, and packing, shown 40 and described, whereby the gas is separated from the water, substantially as set forth.

2. In an apparatus for administering anaesthetic gases, the combination of a gas-tight floating partition, A², opening g, inlet-pipe A³, 45 gas-holder A, and cistern B, whereby the gas is kept from contact with the water, substantially as set forth and described.

3. In an apparatus for administering anaesthetic gases, the combination of cistern B, gas-holder A, weight-seat and weights, floating partition A², packing 3, opening g, supply-pipe A³; and detachable open-bottomed floats A⁴, substantially as and for the purposes set forth.

4. In an apparatus for administering anaesthetic gases, a gas-holder having detachable chambers A⁵ secured to lower inner surface of holder, said chambers being open at the bottom and acting as floats, substantially as set 60 forth.
